FIN CONSTRUCTION

Charles E. Lucke, New York, N. Y., assignor to
United Aircraft Corporation, East Hartford,
Conn., a corporation of Delaware

Application October 8, 1941, Serial No. 414,141

3 Claims. (Cl. 257—261)

This invention relates to improvements in heat transfer devices and has particular reference to improvements in heat transfer devices of an externally finned cylindrical type such as the cylinders of internal-combustion engines.

An object of the invention resides in the provision of an improved fin and jacket structure for heat exchange devices, such as internal-combustion engine cylinders, particularly arranged to reduce energy losses in the flow of cooling air applied to the devices.

A further object resides in the provision of improved heat transfer and air controlling means of the character indicated particularly designed to improve the distribution of cooling air and facilitate the entry of the air into and out of the heat transfer structure.

Other objects and advantages will be more particularly pointed out hereinafter or will become apparent as the description proceeds.

In the accompanying drawing, in which like reference numerals are used to designate similar parts throughout, there is illustrated, in several modified forms, a suitable embodiment for the purpose of disclosing the invention. The drawing, however, is for the purpose of illustration only and is not to be taken as limiting or restricting the invention since it will be apparent to those skilled in the art that various changes in the illustrated embodiment may be resorted to without in any way exceeding the scope of the invention.

In the accompanying drawing, Fig. 1 is a somewhat schematic transverse sectional view through a group of engine cylinders showing fins and jackets, constructed according to the invention, applied thereto.

Fig. 2 is an elevational view of an engine cylinder showing a jacket and fin arrangement, constructed according to the invention, applied thereto.

Fig. 3 is a somewhat schematic sectional view of a single engine cylinder showing a somewhat modified form of jacket and fin arrangement constructed according to the invention applied thereto.

Fig. 4 is a transverse sectional view of a fragmentary portion of an engine cylinder jacket and fin construction showing a modified form of air entrance opening in the jacket and fin arrangement, and

Fig. 5 is a transverse sectional view similar to Fig. 4 showing a still further modified form of air entrance opening.

It is at present common practice to provide

heat exchange bodies such as engine cylinders with external annular fins for transferring heat from the cylinders to a stream of cooling air flowing past the cylinders and it is also known to provide jackets or baffles for closing off the inter-cylinder spaces and constraining all of the air passing through the engine to flow through the inter-fin spaces around the engine cylinders and cylinder heads. In all known arrangements the fins, and particularly the cylinder barrel fins, extend entirely around the individual cylinders and maintain substantially the same radial depth and the same spacing for the entire cylinder circumference and the cooling air entrance spaces provided in the baffles or jackets expose the peripheral edges of the fins to the entering stream of cylinder cooling air. It is conceived that this arrangement causes large losses in the energy of the cooling air stream and is also responsible for an unequal distribution of air flow around the opposite sides of the various cylinders and a fluctuation of cooling air flow over particular cylinder areas. It is among the objects of the present invention to facilitate the entrance of the cooling air to, and exit from the finned areas of the cylinders to thereby minimize the losses in the energy of the cooling air stream and also to substantially equalize the distribution of the cooling air around the cylinders and maintain the air flow in a steady condition to promote heat transfer to the cooling air stream as it passes into and through the heat exchange structure.

With these objects in view, the fins are divided at the upstream and downstream sides of the cylinders, with reference to the direction of cooling air flow, by providing suitable registering notches in the individual fins, as particularly illustrated in Figs. 1, 3, 4 and 5. In Fig. 1 the numerals 10 and 12 generally indicate two cylinders of the forward row of a two row radial engine and the numeral 14 generally indicates a cylinder of the rear row. In Figs. 4 and 5 the numeral 10 generally indicates a cylinder, which may be any one of the cylinders mentioned above or may be a cylinder of an entirely different type of air-cooled engine since the arrangement shown in Fig. 1 is for convenience in illustration only and the invention is in no way limited to any particular type of engine or any particular arrangement of engine cylinders. The cylinder, generally indicated by the numeral 10 in Fig. 2, may also be the cylinder of any desired type of air-cooled engine having any desired cylinder arrangement and the cylinder generally indicated

at 16 in Fig. 3 may also have any of the applications indicated above since the principal difference between the form of the invention shown in Figs. 1 and 3 resides in a modification of the jacket shown in Fig. 3.

The fin notches, as indicated at 18 for the upstream notches and 20 for the downstream notches, divide each fin into two parts disposed at opposite sides of the cylinder, as indicated at 22 and 24. Jacket sections as indicated at 26 and 28 overlie these respective fin portions substantially or actually in contact with the peripheries thereof, the jacket portions terminating at the corresponding sides of the fin notches, as is clearly illustrated, to provide air entrance and exit openings in the jacket structure. Along the edges of these openings the edges of the jacket portions are slightly curved and may be bent inwardly into positive contact with the fin peripheries, as is particularly shown in Fig. 1, or may be beaded outwardly, as indicated at 30 in Figs. 4 and 5, to provide an easier entrance opening for the cooling air.

Preferably the notches or gaps between the adjacent ends of corresponding fin portions are of sufficient size to provide air entrance and exit openings the lateral halves of the circumferential boundaries of which have an area at least as great as the frontal area of the inter-fin spaces at the corresponding side of the cylinder to provide a free rather than a restricted entrance or exit opening for the cooling air.

The notches separating the two portions of the individual fins may be of the same shape or may be of different shapes, as may be found most advantageous in any particular installation, and the notch shape may vary, several different shapes being shown by way of example in Figs. 1, 4 and 5. In Fig. 1 the notch is constituted by a simple partly circular cut out while in Fig. 4 it is formed by a V shaped cut out having substantially straight sides and in Fig. 5 it is formed by intersecting circles giving substantially convex end portions to the opposite fin portions. Any one of these various forms or any other form found to be especially advantageous in any particular installation may be used without in any way exceeding the scope of the invention.

It is also within the scope of the invention to provide separate fin portions of somewhat less than semi-circumferential extent with the adjacent ends of corresponding fin portions at the same side of the cylinder separated by a space or gap. This construction has particular application where the fins are attached to the cylinder rather than being formed integrally therewith.

In the form of the invention shown in Fig. 3 the cylinder and fin construction may be the same as that shown in Fig. 1 but in this case the jacket portions 32 and 34 are shown provided with extensions at the air entrance and air exit locations, the air entrance extension being indicated at 36 and the air exit extension being indicated at 38. The extension 38 may be provided with an outwardly flared or beaded end portion 40 to facilitate the entrance of cooling air or may, if desired, be connected to a suitable cooling air conduit, not illustrated, which may lead from some portion of the airplane such as a wing leading edge, and may include an induction fan if such a feature is desirable. The air exit extension 38 may lead into the space within the cowl at the rear of the engine or may, if desired, be connected with a cooling air exhaust collector which may be led to the exterior of the aircraft.

at some suitable location and which may include exhaust gas actuated means for inductively increasing the flow of cooling air through the engine.

5 It is also contemplated to provide vanes or separators, as indicated at 42 and 43 in Fig. 1, to divide the airflow and insure an equal flow of air around the opposite sides of the various cylinders in those installations where there is a 10 tendency for the air to divide unequally or to fluctuate in its passage in opposite directions around the individual cylinders. Such vanes or dividers may be applied to all of the cylinders in a particular engine installation or may be applied only to those cylinders with which particular difficulty is experienced in obtaining an equal airflow around both sides thereof.

In addition the advantages enumerated or inferred above, a further advantage resides in the 20 division of the annular fins into separate portions in that this division relieves stresses in the fin structure, particularly those stresses incident to heat expansion of the cylinders. This advantage may be found of particular importance 25 where the cylinder and fins are formed of different materials.

While a suitable mechanical embodiment in 30 several slightly modified forms has been hereinabove described and illustrated in the accompanying drawing for the purpose of disclosing the invention, it is to be understood that the invention is not limited to the particular embodiment so illustrated and described, but that such changes in the size, shape and arrangement of 35 the various parts may be resorted to as come within the scope of the subjoined claims.

Having now described the invention so that others skilled in the art may clearly understand the same, what it is desired to secure by Letters Patent is as follows:

1. Cooling means for an air cooled cylinder comprising, circumferential fins extending outwardly from the exterior surface of said cylinder, said fins being spaced apart in a direction axially of said cylinder, a jacket surrounding said cylinder and said fins and forming with said cylinder a cooling air passage for directing cooling air over said cylinder and said fins, air entrance and exit openings in said jacket for passing cooling air through said passage, said fins having cut-away portions immediately underlying said air entrance opening in said jacket.

2. Cooling means for an air cooled cylinder comprising, circumferential fins extending outwardly from the exterior surface of said cylinder, said fins being spaced apart in a direction axially of said cylinder, a jacket surrounding said cylinder and said fins and forming with said cylinder diametrically opposed cooling air passages for directing cooling air over said cylinder and said fins, air entrance and exit openings in said jacket at opposite sides thereof for passing cooling air through said passages, said fins having cut-away portions immediately underlying each of said openings in said jacket, and a vane bisecting at least one of said jacket openings and the respective cut-away portions for dividing the air passing through said opening between said opposed cooling air passages.

3. The arrangement as set forth in claim 1 in which the edges of at least one of said jacket openings are curved to facilitate the flow of air into or out of said openings.
